UNITED STATES PATENT OFFICE.

CHARLES S. WHIPPLE, OF BOSTON, MASSACHUSETTS, ASSIGNOR OF ONE-HALF TO DAVID HUNT, OF SAME PLACE.

DOOR-SECURER.

SPECIFICATION forming part of Letters Patent No. 592,854, dated November 2, 1897.

Application filed March 15, 1897. Serial No. 627,459. (No model.)

To all whom it may concern:

Be it known that I, CHARLES S. WHIPPLE, of Boston, county of Suffolk, State of Massachusetts, have invented an Improvement in 5 Detachable Door-Fastenings, of which the following description, in connection with the accompanying drawings, is a specification, like letters on the drawings representing like parts.

10 This invention has for its object to improve and simplify the construction of detachable door-fasteners; and it consists in certain details of construction, which will be hereinafter more fully set forth and claimed.

15 Figure 1 shows in plan view a detachable door-fastening embodying this invention; Fig. 2, a side view of the detachable door-fastening shown in Fig. 1; and Fig. 3, a cross-section of the door-fastening shown in Fig. 1, 20 taken on the dotted line 11.

a represents a flat strip of metal having one of its ends bent at substantially right angles to the main portion, as at *a'*, and having secured to its opposite end a block *a²*, through 25 which a threaded hole is formed, and adjacent said block the strip *a* is slotted for a considerable distance, as at *a³*, in line with said hole.

b represents a plate bent or folded upon it- 30 self to astride the strip *a*, as shown, said strip being set edgewise and to be moved along on said strip freely in either direction, and said bent plate *b* has at one end two wings or lateral projections *b'*, extended outward in opposite ways.

35 A thumb-screw *c* passes through the block

a² and bears upon or against the end of said bent plate *b* to adjust and hold it in its different adjusted positions.

In using the device the right-angular end 40 *a'* of the strip *a* will be inserted in a hole or slot in the jamb or frame of the door—as, for instance, in a hole in the striker-plate—and the strip *a* when set edgewise will occupy a position between the edge of the door and its 45 frame, and the bent plate *b* on said strip *a* will be adjusted with its wings or lateral projections *b'* bearing one upon the door and the other upon its frame, and then by turning in the thumb-screw *c* said bent plate *b* will be 50 moved along on said strip *a*, and its wings or lateral projections bearing more firmly against said door and its frame will firmly clamp the device in position.

The bent plate *b*, it will be observed, may 55 be detached from the strip *a*.

I claim—

The detachable door-fastening herein described consisting of the strip *a* having a right-angular portion *a'* at one end, a block *a²* at 60 the opposite end and a slot *a³*, the bent plate *b* astride and moving along on said strip *a* having lateral projections *b'*, *b'*, and a thumb-screw *c* passing through said block and working in said slot *a³* against said bent plate *b*. 65

In testimony whereof I have signed my name to this specification in the presence of two subscribing witnesses.

CHARLES S. WHIPPLE.

Witnesses:

B. J. NOYES,
HARRY O. ROBINSON.
